Primary Examiner — David G Muller*Assistant Examiner* — Nathan M Johnston(74) *Attorney, Agent, or Firm* — Venable LLP; Steven J. Schwarz; Miguel A. Lopez(57) **CLAIM**

The ornamental design for a detachable cover for boreholes in rack and wall units, as shown and described.

DESCRIPTION

FIG. 1 is a perspective view for a detachable cover for boreholes in rack and wall units showing my new design.

FIG. 2 is a rear elevation view thereof.

FIG. 3 is a side elevation view thereof, wherein the left side elevation and right side elevation views are identical; and, FIG. 4 is a front elevation view thereof.

The features shown in broken lines are disclaimed.

1 Claim, 4 Drawing Sheets(56)
